Attorneys,

UNITED STATES PATENT OFFICE.

WILLIAM FRANCIS DENLIS, OF COTTONWOOD, CALIFORNIA.

BALING-PRESS.

SPECIFICATION forming part of Letters Patent No. 372,842, dated November 8, 1887.

Application filed August 18, 1887. Serial No. 247,296. (No model.)

To all whom it may concern:

Be it known that I, WILLIAM FRANCIS DENLIS, a citizen of the United States, residing at Cottonwood, in the county of Shasta and State of California, have invented new and useful Improvements in Baling-Presses, of which the following is a specification.

My invention relates to improvements in baling-presses; and it consists in certain novel features of the operating mechanism, as will be hereinafter first fully described, and then pointed out in the claims.

In the accompanying drawings, which fully illustrate my invention, Figure 1 is a perspective view of my improved hay-press. Figs. 2 and 3 are vertical longitudinal sections of the same, and Fig. 4 is a detail perspective view showing the toggle-lever with its rollers and supporting-bracket.

Referring to the drawings by letter, A designates the main or body portion of the press, the bottom or floor B of which is extended from one end, as shown, and C C designate two braces which extend from the end of the extended portion of the base to the upper ends of two standards, D D, erected on opposite sides of the extended portion of the base at the end of the main or body portion of the press, as shown. The extended portion of the base is provided with a central longitudinal slot, E, and on its upper side, just beyond the outer end of the said slot, is secured a bracket, F, which has one arm secured to the base and its other arm extending upward substantially parallel to the braces C C. To the upper end of this inclined arm of the bracket I pivotally connect one end of a toggle-lever, G, the opposite end of which is pivotally connected to the rear side of the plunger H, moving in the baling-chamber. The toggle-lever is composed of two parts hinged together; and it is provided with two grooved pulleys, I I, which are arranged on its opposite sides at the hinged connection of its parts.

J J designate two ropes, which are secured at one end to the transverse bolt or rod K, secured in the braces C C, and thence extend down under and around the pulleys I I, and then upward to the enlarged curved end L of the operating-lever M, around which they pass and to which they are secured. This operating-lever is fulcrumed at or near its enlarged

end upon a bolt or rod, N, secured transversely in the upper ends of the standards D D.

O designates a rope, which has one end connected to the extremity of the operating-lever, and then extends downward under and around a pulley or roller, P, at the end of the base of the press, and then extends outward, to be attached to an engine or other source of power. 55

Q designates a check-rope, which has its opposite ends secured to the operating-lever and the braces C C, respectively; and R designates a coiled spring, which has its opposite ends secured to the toggle-lever near its joint and 65 to the base near the outer end of the slot E.

In operation the hay is placed in the baling-chamber of the press in the usual manner. Power is then applied to the rope O to depress the outer end of the operating-lever, thereby 70 elevating the inner end and drawing on the ropes J J, which will straighten and extend the toggle-lever, thereby forcing the plunger into the baling-chamber. The power is now removed from the rope O, and the spring R 75 draws the several parts back to their normal position. The check-rope Q prevents the operating-lever being carried too far upward, and holds it in the proper position for a repetition of the former operation. 80

Having thus described my invention, what I claim, and desire to secure by Letters Patent, is—

1. In a baling-press, the combination of the braces, the operating-lever, the bracket arranged between the lower ends of the braces, the toggle-lever arranged below the operating-lever and connected to said bracket and to the plunger, ropes connected to the operating-lever and to the braces to extend the toggle-lever, and a spring to return said lever to its normal position, as set forth. 85

2. In a baling-press, the combination of the braces, the operating-lever fulcrumed at the upper ends of said braces, the check-rope secured to the operating-lever and to the braces, the bracket arranged between the lower ends of the braces, the toggle-lever secured to said bracket and to the plunger, the return-spring, and the ropes secured to the operating-lever 95 and to the braces to extend the toggle-lever, substantially as set forth. 100

3. The combination of the braces, the operating-lever, the check-rope, the toggle-lever

having pulleys on opposite sides of its hinge, the ropes having their opposite ends secured, respectively, to the operating-lever and to the braces above the toggle-lever, their intermediate portions passing around the pulleys on the toggle-lever, and the return-spring, substantially as specified.

In testimony that I claim the foregoing as my own I have hereto affixed my signature in presence of two witnesses.

WILLIAM FRANCIS DENLIS.
